United States Patent Office

Des. 200,110
Patented Jan. 19, 1965

200,110

AMUSEMENT VEHICLE

David E. Bradley, Jr., 749 Via Somonte,
Palos Verdes Estates, Calif.

Filed June 22, 1964, Ser. No. 80,508

Term of patent 14 years

(Cl. D34—15)

Fig. 1.

Fig. 2.

FIG. 1 is a side elevational view of an amusement vehicle showing my new design;

FIG. 2 is an elevational view of the side opposite that shown in FIG. 1;

FIG. 3 is a front view;

FIG. 4 is a rear view; and

FIG. 5 is a top view of the same.

I claim:

The ornamental design for an amusement vehicle, as shown.
